UNITED STATES PATENT OFFICE

2,665,123

APPARATUS FOR TREATING GASES WITH LIQUIDS

David Blythe Foster, London, and William Stephens Norman, Hoole, Chester, England, assignors to C. D. Patents Limited, London, England, a British company

Application May 22, 1950, Serial No. 163,432

Claims priority, application Great Britain May 26, 1949

4 Claims. (Cl. 261—108)

1

This invention relates to improvements in apparatus for treating gases or vapours with liquids as in scrubbing towers, cooling towers and the like. It is known that many industrial gases or vapours which call for scrubbing treatment contain corrosive ingredients and likewise the liquids employed may contain or acquire corrosive ingredients. It has been customary to use for such towers a packing made of earthenware or of wood or metal; metallurgical coke has also been used as a packing. None of these materials is ideal for the purpose: metallurgical coke is neither efficient or uniform: earthenware (rings for example) also gives irregular results and both those well-known forms of packing are apt to give excessive resistance to the flow of gas or vapour. Wood and metal lend themselves to the production of lattice work which is advantageous but metal corrodes and wood is inclined to perish.

According to this invention in apparatus for treating gases or vapours with liquids (particularly with liquid films flowing over solid surfaces) a packing is used composed of grids or lattices of hard, wettable carbon.

The carbon may be moulded in strip form, fired to produce a strong and durable material and thereafter cut and assembled into the desired grids or lattices.

Thus finely comminuted carbonaceous material such as coal with added plasticising agents such as pitch or tar and/or naphthalene oil (in the form of a paste) may be extruded into a tape of substantially rectangular section and fired to produce the strong and durable carbon and the strip can be sawn or cut and slotted to enable grids or lattices to be built up.

Slight departures from a rectangular section e. g. a double concave section may have advantages such as increasing the contact area.

The extruded section may have fine ribs or grooves lying in a direction normal to the directions of liquid and gaseous flow to increase the friction between the liquid and the carbon and to promote the wetting of the carbon by the liquid.

One process for making the carbon strip suitable for the grids or lattices is that described in United States Patent No. 2,637,072, issued May 5, 1953, to Charles D. Greaves and William D. Parker, and assigned to the owner of the present application.

Practical applications of this invention will be appreciated from the following description of examples reference being made to the accompanying drawings in which:

2

Figure 1 is a perspective view of a scrubbing tower part of the casing being broken away to show the disposition of the carbon grids;

Figure 2 is a side elevation and transverse section of one form of carbon grid; and

Figure 3 is a side elevation and transverse section of another form of carbon grid.

Referring to Figure 1 a casing for an upright scrubbing tower is built up of sections in the form 10 of hollow rectangular prisms 12 having horizontal flanges 13 secured (e. g. welded) to their joining edges, the contiguous flanges being bolted together as indicated at 14. Near the bottom of the tower is an inlet 15 (e. g. an inlet for a gas to 15 be scrubbed) and the tower is also provided with any other necessary inlets and outlets (not shown). Thus in well-known manner the top of the tower may have a liquid distributor which supplies thin films of liquid substantially uniformly over the surfaces of the uppermost grids 20 or lattices.

The filling of the tower consists of horizontal grids or lattices 16 of hard, wettable carbon and the individual elements of each grid or lattice are 25 supported at their ends on horizontal bars 17 of hard carbon, and said bars 17 are spaced apart by simple distance pieces which are also of hard carbon.

The individual elements 16 of the grids or lattices 30 may be made from moulded or extruded strip or may be moulded to the desired form and dimensions but in each case the moulded strip or element is fired as described in the prior specification above referred to, to produce the hard, wettable carbon over which the liquid films will 35 flow evenly.

Referring to Figure 2 the individual elements 18 (which may be made from extruded strip) are of double concave section.

Referring to Figure 3 the individual elements 19 have fine ribs or grooves 20 lying in a direction normal to the directions of liquid and gaseous flow to increase the friction between the liquid and the carbon and to promote the wetting of the carbon by the liquid.

We claim:

1. Apparatus for treating gases or vapours with liquid films flowing over solid surfaces, which apparatus comprises a vertical container 50 and a plurality of horizontal grids spaced above one another in said container, each grid comprising a plurality of spaced, parallel strips of hard, wettable carbon, each of which strips has wide upright sides and has its lower edge serrated to provide downwardly projecting points, the strips

of adjacent grids being disposed at right angles to one another and each downwardly projecting point being arranged a short distance directly above a strip in the grid next below.

2. Apparatus for treating gases or vapours with liquid films flowing over solid surfaces, which apparatus comprises a vertical container, a plurality of horizontal grids disposed one above another in said container, each grid comprising a plurality of parallel strips of hard, wettable carbon, each of which strips has wide upright sides, has its lower edge serrated to provide downwardly projecting points and has its ends slotted, and horizontal bars of hard carbon accommodated in said slotted ends thereby spacing said strips apart, the strips of each grid extending in a direction at right angles to the strips of each adjacent grid, and hard carbon distance pieces spacing said grids above one another, each downwardly projecting point being disposed directly above and out of contact with the upper edge of a strip of the grid next below.

3. Apparatus as claimed in claim 1 in which

the upright sides of each strip are smooth and uninterrupted and are concave, whereby the cross-section of each strip is of double concave form.

4. Apparatus as claimed in claim 1 in which each strip is of narrow rectangular cross-section and the upright sides of each strip are provided with fine horizontal grooves.

DAVID BLYTHE FOSTER.
